(57) **CLAIM**

We claim the ornamental design for a bottle, as shown and described.

DESCRIPTION

FIG. 1 is a perspective view of a bottle showing our new design;

FIG. 2 is a front view thereof;

FIG. 3 is a first side view thereof;

FIG. 4 is a back view thereof;

FIG. 5 is a second side view thereof;

FIG. 6 is a top view thereof; and,

FIG. 7 bottom plan view thereof.

The dash-dash broken lines shown illustrate portions of the bottle. The dot-dash-dot broken lines represent the boundaries of the claim. The broken lines form no part of the claimed design.
